SETTING TOOL AND WELL PACKER

Reuben C. Baker, Coalinga, Calif., assignor to
 Baker Oil Tools, Inc., Vernon, Calif., a corpora-
 tion of California

Application July 10, 1950, Serial No. 172,926

12 Claims. (Cl. 166—63)

1

The present invention relates to subsurface well tools, and more particularly to well packers or anchoring devices, and apparatus for setting such equipment in well bores.

An object of the present invention is to prevent inadvertent loosening or disconnection of a well packer, or other well tool, from a running-in string during lowering of the equipment in a well bore.

Another object of the invention is to provide a thread locking device for preventing inadvertent loosening or separation of a well packer, or the like, from a setting tool, by means of which the packer is anchored in packed-off condition in a well bore.

Another object of the invention is to provide a further object of the invention is to provide a thread lock in subsurface well equipment, which prevents unscrewing between the parts, but which is, nevertheless, easily placed within and removed from the equipment.

Another object of the invention is to provide a setting tool combination, in which the larger portion of the coupling for securing the setting tool to the packer can be pre-assembled or connected to the packer, as in a shop or warehouse, in order to permit the remainder of the setting tool to be associated with the packer at the well in a minimum of time and without any special equipment.

Yet another object of the invention is to provide a wire line setting tool and well packer organization, in which the setting tool is releasably connected to the packer, and in which the setting tool is prevented from inadvertently and prematurely becoming released from the packer.

Still a further object of the invention is to provide a well packer, or similar well tool, in which the possibility of prematurely setting the initially retracted slips of the packer or other tool is largely minimized.

This invention possesses many other advantages, and has other objects which may be made more clearly apparent from a consideration of a form in which it may be embodied. This form is shown in the drawings accompanying and forming part of the present specification. It will now be described in detail, for the purpose of illustrating the general principles of the invention; but it is to be understood that such detailed description is not to be taken in a limiting sense, since the scope of the invention is best defined by the appended claims.

Referring to the drawings:

Figures 1a and 1b together constitute a longitudinal section through a well apparatus, with

2

the parts arranged for running the equipment in a well bore, Fig. 1b being a lower continuation of Fig. 1a;

Fig. 2 is an enlarged longitudinal section through a portion of the apparatus;

Fig. 3 is a cross-section taken along the line 3—3 on Fig. 2;

Fig. 4 is a view similar to Fig. 1b, disclosing the packer portion of the apparatus anchored in packed-off condition within a well casing;

Fig. 5 is a cross-section taken along the line 5—5 on Fig. 1b;

Fig. 6 is a cross-section taken along the line 6—6 on Fig. 4;

Fig. 7 is a section taken along the line 7—7 on Fig. 5;

Fig. 8 is a fragmentary side elevation taken along the curved line 8—8 on Fig. 5;

Fig. 9 is a cross-section taken along the line 9—9 on Fig. 1b;

Fig. 10 is a view similar to Fig. 9 of the slip member expanded against the casing;

Fig. 11 is a section taken along the line 11—11 on Fig. 9;

Fig. 12 is a side elevation taken along the curved line 12—12 on Fig. 9; and

Fig. 13 is an enlarged fragmentary longitudinal section of the lower slip guide arrangement.

In the form of the invention disclosed in the drawings, it is desired to run a well packer A to a desired location in a well casing B disposed within a bore hole. The packer is then anchored in packed-off condition against the well casing through use of a setting tool C connected to it. This setting tool is attached to the lower end of a running-in string D, such as a wire line, extending to the top of the well bore.

The general organization of setting tool C and well packer A is described and claimed in my application for "Apparatus for Operating Tools in Well Bores," Serial No. 80,851, filed March 11, 1949, now Patent No. 2,640,546, patented June 2, 1953.

The packer A includes a tubular body 10 having a body abutment 11 threaded on its lower end, and an enlarged head 12 at its upper end, along which the skirt 13 of a cylinder 14 is slidably mounted. A cylinder head 15 extends inwardly from the lower end of the skirt and slidably engages the external cylindrical surface of the body 10. Body ports 16 provide communication between the interior of the body and the cylinder 14, leakage between the body and cylinder being prevented by the side seal rings 17. The packer disclosed can be run on a tub-

ing string if desired, and set hydraulically, which necessitates the use of the ports 16 and seal rings 17. When the present setting tool C is used, however, the ports 16 and rings 17 may be omitted, although such omission is not essential.

A set of upper segmented slips 18 is disposed around the body 10 immediately below the cylinder head 15. These slips are held initially in retracted position by shear screws 19, attaching them to an upper conical expanded 20 initially secured to the body by one or more shear screws 21. The converging surfaces of the upper set of slips 18 and upper expander 20 are so disposed with respect to one another as to secure the packer A against movement in an upward direction within the casing B, following outward expansion of the slips 18 into engagement with the casing.

A set of lower segmental slips 22 is provided adjacent the body abutment 11, and these slips are also secured by shear screws 23 to a lower tapered expander 24 attached initially to the body 10 by one or more shear screws 25. The direction of taper on the exterior of the lower expander 24 and the taper on the cooperable surfaces of the lower slips 22 are such as to hold the well packer A against movement in a downward direction, following expansion of the slips 22 outwardly against the casing B.

A suitable lock is provided between the body 10 and the upper expander 20 to permit upward movement of the body 10 within this expander, but to preclude its downward movement. Such lock may be of any suitable form. It is illustrated as including a split ring 26 received within a groove 27 in the upper expander and engageable with the downwardly facing ratchet teeth 28 on the body.

A suitable packing 29, such as a packing sleeve, of rubber or similar pliant, elastic material, is disposed around the body 10 between the upper and lower expanders 20, 24. The ends of the packing sleeve are received within annular pockets formed between the expander skirts 30 and the exterior of the body.

In setting the packer A, a downward force is exerted on the cylinder sleeve 14 of sufficient extent to shear the screws 19 attaching the upper slips 18 to the upper expander 20. These slips are then moved downwardly along the upper expander and radially outward into anchoring engagement with the well casing. Such outward expansion of the upper slips 18 can occur, since their retaining shear screws 19 have a lesser combined shear value than the shear screws 21 attaching the upper expander 20 to the packer body 10. These last-mentioned screws have a lesser shear value than the screws 25, 23 holding the lower expander 24 to the body and the lower slips 22 to the lower expander.

After the upper slips 18 have been engaged with the well casing, an upward strain or pull is imparted to the packer body 10, which shears the screws 21 holding the upper expander 20 to the body, and moves the lower expander 24 and lower slips 22 with the body toward the upper expander. This action foreshortens the packing sleeve 29 and effects its outward expansion into firm sealing engagement with the wall of the casing B.

Thereafter, an increase in the upward pull or force on the packer body 10 substantially simultaneously shears the screws 25, 23 holding the lower expander 24 to the body and the lower slips 22 to the lower expander, causing the lower

body abutment 11 to shift the lower slips 22 upwardly along the lower expander and radially outward into anchoring engagement with the wall of the casing. The split, contractible lock ring 26 then engages the ratchet teeth 28 formed on the body to lock the latter against downward movement, since such downward movement is transmitted through the upper expander 20, packing 29, lower expander 24 and lower slips 22 to the well casing B. Upward movement of the body is resisted by the engagement of the lower abutment 11 with the lower slips 22, the upward force being transmitted from the latter through the lower expander 24, packing sleeve 29, upper expander 20 and upper slips 18 to the well casing B (see Fig. 4).

In the manner just described, the well packer A is anchored in packed-off condition against longitudinal movement in both directions within the well casing B.

The well packer disclosed is designed primarily for use in producing oil and gas wells. It has a central bore or passage 31, which can be closed by a flapper valve head 32 pivoted on the abutment 11 and urged by a spring 33 to closed position against a body abutment valve seat 34. A slotted junk pusher and feeler 35 may be attached to the abutment 11 to prevent premature setting of the packer during its descent in the well casing.

It is desired to provide an arrangement which will enable the well packer A to be run in the well casing B in a rapid manner. Such expeditious lowering of the well packer in the well casing can be accomplished through use of a wire line D. It is desired to set the packer fully and firmly against the casing without imposing a strain on the wire line. A substantially large strain or pull on the packer parts may be required, and for this reason, the mechanism for setting the packer must be capable of transmitting a large force and of automatically releasing itself from the well packer when the desired maximum force has been exceeded. Moreover, it is desired to set a type of packer which is used primarily in the production of oil, gas, and the like, and which has the unobstructed central passage 31 therethrough, in order to permit subsequent movement of production equipment into or through the packer.

The above purposes are effectuated with the equipment disclosed in the drawings. As shown therein, setting of the well packer is dependent upon the development of a gas pressure within the setting tool C secured initially to the well packer. This gas pressure is developed within the upper portion of a cylinder 36, consisting of a generally cylindrical sleeve 37, an upper head 38 threaded into the sleeve, and also a lower head 39 threaded into the sleeve.

A motivating gas under pressure is generated in the cylinder, and this force is imposed upon a piston 46 slidably mounted in the cylinder. This piston 46 has one or more ring grooves 47 in its periphery for the accommodation of seal rings 48, to prevent leakage between the piston 46 and cylinder sleeve 37. As disclosed, these rings 48 may consist of rubber, round in cross-section, to guard against leakage in both directions.

The upper end of a piston rod 49 is threaded to the piston 46, the rod extending downwardly through the lower cylinder head 38 to a point therebelow, where an anvil or cross-piece 50 is mounted within a transverse slot 51

in the rod. Leakage between the rod 49 and lower cylinder head 39 is prevented by suitable rod packing 52, in the form of one or more round rubber or rubber-like seals, engaging the periphery of the rod and disposed within suitable ring grooves 53 in the head. The packing or seal rings 52 prevent leakage of liquids from the well casing into the cylinder below the piston 46, insuring that air under atmospheric pressure is present below the piston 46 when the apparatus is assembled and lowered in the well casing.

It is desired to transfer the downward movement of, or force imposed upon, the piston 46 and the piston rod 49 to the upper slips 18 of the packer, and the relative upward movement of the cylinder 36 to the packer body 10, in order to obtain the desired anchoring of the packer in the well casing, in the manner described above. To accomplish this purpose, a tubular actuating mandrel 54 is threadedly connected to the lower cylinder head 39. The lower end of this mandrel 54 is coupled to the packer body 10 through the agency of a frangible connecting device. As specifically disclosed, the lower end of the mandrel 54 is threaded into an adjuster sub 54a, which is threaded onto the upper end of a tension rod 55 extending downwardly within the packer body 10. The lower end of this rod is threaded into a tension head 56 screwed onto the upper end of a releasing stud 57 having an intermediate portion 57a of reduced diameter. The lower end of this stud is threaded into a depending shank 58, that is, in turn, secured to a latch retaining abutment 59 having an upward and inwardly inclined face 60. The cylindrical portion 61 of the abutment engages the packer valve head 32, to hold it in open position.

Any upward force imposed upon the tension rod 55, tension head 56, releasing stud 57, shank 58 and retaining abutment 59 is adapted to be imparted to the packer body 10. This force is transferred from the inclined face 60 of the retaining abutment onto companion inclined, inner faces 62 on latch feet 63 integral with spring-like leg members 64 forming the lower portion of a latch sleeve 65, which extends upwardly to a point along the tension head 56. At this point, the sleeve is provided with an inturned shoulder 66 that can be spaced upwardly from a lower flange or shoulder 67 on the tension head 56. The outer inclined faces 68 of the latch feet engage the valve seat 34 on the body abutment 11, and serve to transmit any upward force imposed on the retaining abutment 59 directly to the packer abutment 11, which forms part of the packer body 10.

When the parts forming the mechanism for coupling or locking the tension rod 55 and tension head 56 to the packer abutment 11 occupy the position shown in Figs. 1b and 4, the latch sleeve shoulder 66 is disposed a substantial distance above the tension head shoulder 67. The inclined face 60 of the retaining abutment 59 bears upon the inclined faces 62 of the latch feet 63 and tends to urge and hold them outwardly against the valve seat 34. Such outward movement may be limited by engagement of the lower portions 69 of the spring legs 64 with the inner surface 70 of the packer abutment.

Upon the exertion of sufficient tension on the releasing stud 57 to pull it apart, the shank 58 and retaining abutment 59 may drop downwardly, as explained in my above-identified application, to remove the abutment 59 from its retaining

position behind the latch feet 63, and allow the latter to be disengaged from the packer abutment 11. The latch retaining abutment 59 and its shank 58 can drop to the extent limited by the engagement of its shoulder 71 with an inwardly directed flange 72 on a retrieving sleeve 73 threaded onto the lower end of the tension head 56.

Following disruption of the releasing stud 57 and dropping of the latch retaining abutment 59, upward movement on the tension rod 55 will lift the tension head 56 with it, causing the shoulder 67 on the latter to engage the upper shoulder 66 on the latch sleeve 65, pulling the latch legs 64 and their foot portions 63 upwardly and inwardly within the packer body 10. Such upward movement of the tension rod 55 and tension head 56 also causes the retrieving sleeve shoulder 72 to engage the shoulder 71 on the shank 58 and elevate the retaining abutment 59 through the packer. It is to be noted that all of the locking elements, with the exception of the spring-like foot portions 63 on the latch sleeve 65, are smaller in diameter than the internal diameter of the passage 31 through the packer body 10. Since the spring-like feet 63 and legs 64 can flex inwardly, the entire locking mechanism may be removed from a set well packer A, and removed with the remaining portions of the setting tool C to the top of the well bore. It is also to be noted that the initial distance between the latch sleeve shoulder 66 and tension head shoulder 56 is substantially less than the distance between the shank shoulder 71 and retrieving sleeve shoulder 72. This disparity in distance insures against the abutment 59 again moving within the latch feet 63 during elevation of the setting tool after disruption of the stud 57.

The piston rod 49 is movable downwardly within the bore 75 of the actuating mandrel 54, the cross-piece 50 projecting in opposite directions from the rod 49 through diametrically opposed longitudinally extending slots 76 formed through the mandrel wall. The cross-piece 50 also extends into opposed slots 77 formed through a setting ring or sleeve 78 slidably mounted on the actuating mandrel 54, to form a connection between the piston rod and the setting ring 78. A setting sleeve or skirt 79 is adjustably threaded on the setting ring 78, the lower portion of the skirt being secured to a ring 80 resting on top of the packer cylinder sleeve 13.

As indicated above, a gaseous force or pressure is imposed upon the piston 46. This force moves the piston and piston rod 49 downwardly and the cylinder 36 in a relative upward direction. The downward movement of the rod 49 is transmitted to the ring 80 through the anvil 50, setting ring 78, and sleeve 79; whereas, the upward movement of the cylinder 36 is transmitted to the packer body 10 through the actuating mandrel 54, sub 54a, tension rod 55, tension head 56, stud 57, shank 58, abutment 59, latch feet 63, and body abutment 11. Accordingly, it is apparent that the development of sufficient pressure in the cylinder 36 acting upon the piston 46 will eventually shear the screws 19 holding the upper slips 18 to the expander 20, and move the slips outwardly against the casing. Thereafter, the cylinder 36 will move upwardly to move the body 10 in the same direction for the purpose of expanding the packing sleeve 29 against the casing B, and the lower slips 22 against the casing, in the manner described above.

In order to obtain the desired operational sequence, a combustible fuel or power charge 81

may be contained within the upper end of the cylinder 36. The combustion charge, such as a railway flare of cylindrical or stick form, is placed in the upper head end 38 of the cylinder 36 within a combustion chamber 82 formed therein. The charge is ignited by a blank cartridge 83 contained within a gun barrel 84 inserted within the upper end of the upper cylinder head 38. Leakage between the barrel and head is prevented by suitable side seals 85 on the barrel engaging the wall of the head.

The barrel 84 is threaded into a cable head 86, which, in turn, is threadedly secured to the upper end of the cylinder head 38. The wire line running-in string D is suitably secured to the cable head 86, in a known manner, and has the lower end of its electrically conductive wire or core 87 connected electrically to a heating filament 88 contained within the cartridge 83.

The apparatus is lowered in the well bore with the parts in the position shown in Figs. 1a and 1b. When the depth in the casing B is reached at which the well packer A is to be set, the electrical circuit through the cartridge filament 88 is completed, which fires the cartridge 83. The flame issuing therefrom ignites the upper end of the power charge 81, initiating its combustion. This charge contains its own source of oxygen to support combustion. As combustion proceeds, a gaseous pressure is developed within the cylinder 36 above the piston 46. As the pressure increases, the piston 46 is urged downwardly and the cylinder 36 relatively upwardly. The force imposed on the piston is transmitted through the rod 49, cross-piece 50, and setting ring 78 to the sleeve 79, ring 80 and cylinder 14, which bears against the upper slips 18. Downward movement of the lower piston 46 takes place against the relatively slight resistance of the air in the cylinder 36 below the piston 46, which is initially at atmospheric pressure, and also against the hydrostatic head of fluid in the well casing acting upwardly across the cross-sectional area of the piston rod 49. When sufficient pressure has been developed within the cylinder 36 by the gaseous medium, and has been transmitted to the slips 18, to overcome the shear strength of the shear screws 19, and also the hydrostatic head of fluid acting upwardly on the piston rod 49, the slips 18 are released from the expander 20 and are pushed downwardly along the latter into outward engagement with the casing B.

As the combustible charge 81 continues to burn, the gas pressure within the cylinder 36 increases to a further extent, and this increased pressure or force is transmitted to the lower piston 46. Since the upper slips 18 are wedged against the casing, the piston 46 cannot move downwardly to any further appreciable extent. Instead, the cylinder 36, actuating mandrel 54, sub 54a, tension rod 55, tension head 56, stud 57, shank 58, latch retaining abutment 59, latch feet 63, abutment 11 and its packer body 10 are urged in an upward direction. When the pressure and force within the cylinder 36 has increased sufficiently to overcome the shear strength of the screws 21 holding the upper expander 20 to the body 10, such screws are disrupted and the packer body is moved upwardly within the upper expander 20 to compress the rubber packer sleeve 29 between the upper and lower expanders 20, 24, forcing it into firm sealing engagement with the casing wall.

Further increase in the cylinder gas pressure, as a result of the continued combustion of the

charge 81, effects shearing of the screws 25, 23 attaching the lower expander 24 to the body 10 and the lower slips 22 to the lower expander, allowing the cylinder 36 to move upwardly and carry the body 10 and lower slips 22 in an upward direction to shift the latter radially outward into engagement with the casing.

The pressure in the cylinder 36 continues to increase, as combustion of the charge 81 proceeds, and all of the packer elements are engaged more firmly with the casing B. When the pressure exceeds the tensile strength of the reduced diameter portion 57a of the releasing stud 57 securing the actuating mandrel 54 indirectly to the body 10, this stud 57 is pulled apart at its reduced diameter portion 57a to release automatically the setting tool C from the well packer.

As was indicated above, such release of the setting tool occurs as a result of dropping of the latch retaining abutment 59 and the shank 58 to the extent limited by engagement of the shank shoulder 61 with the flange 72 of the retrieving sleeve 73. This dropping removes the latch retaining abutment 59 from its holding position behind the latch feet 63 and allows the latter to be pulled upwardly with the remainder of the setting tool C during elevation of the latter. This upward pulling occurs because of engagement of the tension rod shoulder 67 with the inturned shoulder 66 on the latch sleeve 65. Of course, the shank 58 and latch retaining abutment 59, as well as the lower broken portion of the releasing stud 57, are also elevated through the well packer A with the remainder of the setting tool, since these elements are supported by the retrieving sleeve flange 72.

Accordingly, it is apparent that all of the setting tool mechanism C is released from the set and anchored well packer A, and the entire mechanism elevated by means of the wire line D to the top of the well bore.

After the setting tool has been removed from the well casing, production equipment (not shown) may then be run in the well casing for suitable coaction with the well packer A in producing the well from one or more zones below the well packer. The central passage 31 through the packer body 10 is unobstructed, except for the lower back pressure valve head 32, which is readily displaced to one side, allowing the production tubing and other equipment to be placed in leakproof engagement with the packer body 10 and also allowing such equipment to extend completely through the packer body, if desired, to a point therebelow.

During lowering of the setting tool C and well packer A organization in the well bore by means of the wire line D, there may be a tendency for relative rotation to occur between the well packer and the setting tool, or between parts of the setting tool itself. As an example, relative rotation may occur between the tension rod 55 and the adjuster sub 54a attached to the lower end of the setting mandrel 54. The threaded connection between the tension rod 55 and adjuster sub 54a is preferably a right-hand one. If relative rotation between the adjuster sub and tension rod is in such a direction as to screw the rod 55 further into the sub, nothing detrimental to the equipment can occur. However, if the direction of rotation is such as to unthread the tension rod 55 from the adjuster sub 54a, and if such unthreading or unscrewing is sufficient in extent, the result may be a complete disconnection between the tension rod and the adjuster sub, which

has the effect of disconnecting or detaching all parts of the setting tool above the tension rod 55 from the coupling portion of the setting tool within the packer A, and of effectively disconnecting the setting tool C from the well packer.

Were the foregoing undesirable action to occur, the well packer A would drop down the casing B and would be lost in the hole.

In order to guard against such undesired release of the major portion of the setting tool from the tension rod 55, a locking device is provided between the tension rod and the adjuster sub. This locking device does not interfere with the threading of the tension rod 55 upwardly into the sub 54a, but it does prevent rotation of the tension rod with respect to the sub in the opposite direction.

The locking device illustrated in the drawings consists of a helical left-hand spring 90 having its lower end 91 fitting within an end groove slot 92 in the upper end of the tension rod 55. This spring is wound left-hand or opposite to the right-hand threads on the tension rod and adjuster sub. The peripheral portions of the spring turns snugly and frictionally engage the inner cylindrical wall 93 of the adjuster sub 54a.

In the event that the tension rod 55 is threaded upwardly into the adjuster sub, such action is not resisted one bit by the lock spring 90, since such right-hand turning of the tension rod twists the spring in the proper direction, to release its periphery from frictional engagement with the wall 93 of the adjuster sub. However, should the tension rod 55 tend to turn in the opposite or left-hand direction, such action would tend to expand the lock spring 90 and urge it more firmly against the wall of the adjuster sub. Thus, the lock spring 90 functions in the nature of a one-way brake, preventing unscrewing of the tension rod 55 in a downward direction from the adjuster sub 54a, but readily permitting its upward threading into the adjuster sub. Accordingly, the lock spring 90 prevents relative rotation between the adjuster sub and the tension rod in a direction which would cause the latter to unthread from the adjuster sub 54a, and allow the well packer A and the lower adapter portion of the setting tool C to drop off the setting mechanism, and be lost in the well bore.

The lock spring 90 is readily inserted in the adjuster sub during assembly of the apparatus, before the tension rod 55 is threaded into the sub. The lock spring need merely be twisted in the proper direction, as to the right, and forced into the sub bore through its upper end until it engages the bottom of the smooth portion 93 of the bore. The tension rod 55 is then threaded into the adjuster sub 54a, its slot 92 receiving the lower end 91 of the lock spring. Thereafter, upward threading of the tension rod can continue, the lock spring merely retracting or releasing itself from the wall 93 of the adjuster sub. Thus, the lock spring does not interfere or offer any material resistance to threading of the tension rod into the adjuster sub to the desired extent. It does, however, as described above, prevent unthreading of the tension rod from the adjuster sub.

When the parts are to be dismantled, the lock spring 90 would prevent unscrewing of the tension rod 55 from the adjuster sub 54a. However, the setting mandrel 54 can be unthreaded from the adjuster sub 54a and the latter then threaded downwardly along the tension rod 55, which action is not interfered with by the lock spring 90,

since turning of the adjuster sub to the right releases the spring from the adjuster sub wall 93. The sub is turned until it is fed downwardly along the tension rod to the extent in which the lock spring 90 is positioned out of the cylindrical bore or passage 93 of the sub, whereupon the lock spring may be lifted out of connecting relation with the tension rod. With the removal of the lock spring, the adjuster sub 54a may then be turned in the opposite direction to unthread it completely from the tension rod 55.

As described above, the latch retaining abutment 59 is held initially in an upward position, with its inclined face 60 engaging the latch feet 63, and thereby coupling the setting tool C to the well packer A. In the event that the abutment 59 were to move downwardly, the latch feet 63 would be released and the well packer might drop downwardly to a position in which the latch feet were retracted and the entire packer disconnected from the setting tool. Such action could occur, for example, in the event that the piston 46 were not at the uppermost end of its stroke, which might allow the cylinder 36 to shift downwardly, this downward motion being transmitted through the setting mandrel 54, tension rod 55, tension head 56, release stud 57 and shank 58 to the retaining abutment 59, shifting it downwardly of the latches 63.

To preclude the aforementioned possibility, a locking or thrust plate 95 is disposed over the tension rod 55 and engages a shoulder 96 in the packer body 10 at the lower end of its threaded box 97. This plate is held in this position by a suitable lock nut 98 threaded on the tension rod and engaging the plate 95, the nut having a plurality of radial pins 99 extending outwardly therefrom for cooperation with a suitable tool (not shown). The lock nut 98 is tightened against the lock plate 95 to the extent necessary to hold the latch retaining abutment 59 in its uppermost position and with its inclined face 60 securing the latch feet 63 outwardly in appropriate engagement with the body valve seat 34.

With the locking plate 95 and lock nut 98 arrangement, any downward forces or thrusts imposed on the tension rod 55 cannot effect downward shifting of the latch retaining abutment 59, since the downward force is transmitted through the lock nut 98 and plate 95 to the packer body 10. However, the nut and plate do not interfere with the disruption of the release stud 57 after the packer A has been fully set, and the consequent dropping down and release of the latch retaining abutment 59 from the latches 63, which effectively disconnects the entire setting tool C from the well packer A and allows the setting tool to be withdrawn to the top of the well bore.

The locking plate 95 and lock nut 98 arrangement also has the function of preventing the tension mandrel 55 from rotating with respect to the packer A, which might tend to effect disconnection of some of the other threaded connections therebelow, as the various threaded connections in the tension head 56, release stud 57, shank 58 and retaining abutment 59.

The locking nut and plate arrangement also permit the lower adapter portion 55, 56, 57, 58, 59, etc. of the setting tool to be assembled in a shop or warehouse before the equipment is transported to the well location, all of which adds to the convenience and ease of relating the various parts of the apparatus to one another. The entire coupling device secured to the lower end of the

tension rod 55, and the tension rod itself, can be mounted in the packer A in the shop, the locking plate 95 and lock nut 98 then being properly mounted in place, together with the adjuster sub 54a and lock spring 96. At the well location, it is merely necessary to secure the setting mandrel 54 in the adjuster sub 54a, and bring the ring 80 attached to the lower end of the setting sleeve 79 into contact with the upper end of the cylinder sleeve 13.

The well packer employs an upper and lower arrangement which insures proper location and spacing of the slip segments when they are shifted outwardly into engagement with the wall of the well casing. The upper slips 18 consist of a plurality of arcuate segments 100 preferably having weakened longitudinal inner grooves 101 which are in alignment with longitudinal peripheral outer grooves or notches 102. The aligned inner and outer grooves 101, 102 form weakened sections along which each segment can break when being wedged against the casing B by the tapered upper expander 20, in order that the smaller segments, into which the slips are broken, can conform more closely to the curvature of the casing wall, and thereby provide a greater anchoring force of the slips 18 in the casing.

When the slips are in a retracted position, they are located in proper spaced relationship by the shear screws 19. However, once these shear screws 19 are disrupted, the slips 18 may not retain their spaced relation in being expanded outwardly against the casing. To insure maintenance of this relationship, each segment 100 is provided with a radial end guide groove 103 in its upper portion, in which a locating pin 104, secured to the cylinder head 15, is slidably received. When the cylinder 14 is moved downwardly to shift the upper slips 18 along the upper expander 20, the shear screws 19 are disrupted and the guiding grooves 103 slide along the locating pins 104, in order to hold the slip segments 100 uniformly spaced with respect to each other, to the full extent of their outward expansion into engagement with the well casing B. Thereafter, the exertion of an adequate wedging force between the expander 20 and slips 18 will break each segment 100 into smaller segments, as described above, with the wickers 105 of the slips firmly embedded into the wall of the well casing, and with all of the slip segments 100 disposed substantially uniformly around the upper expander 20 and well casing B.

A similar arrangement is provided with respect to the lower slip assemblage 22, in which the lower slips also have the longitudinal inner and outer aligned peripheral weakened grooves 101a, 102a. These slips also have the end guide grooves 103a in their large or lower portion receiving the locating pins 104a, which, in this instance, are secured to a washer or disk 106 resting upon the body abutment 11.

During lowering of the equipment in the well bore, the lower slips 22 might encounter some foreign object and become prematurely tripped or expanded. To minimize this possibility, the shear screws 23 securing the slips to the lower expander 24 are supplemented by actually integrating each slip segment 100a to its neighboring slip segment. As a matter of fact, the lower slips 22 are at first integral with one another, the slip assembly being formed from an integral piece of metal having the weakening and guide grooves referred to above. In addition, preferably spaced equi-angularly apart, the slip ring or sleeve has

additional weakening internal grooves 107. This deeper groove 107, in conjunction with an external aligned weakening groove 102a leaves a relatively small metallic bridge 108 between the adjacent segments 100a, holding the segments to one another, and, of course, resisting their outward expansion, since the slip member 22 is at first a solid ring. Assuming that three main slip segments 100a are to be used, the deeper weakening grooves 107 and their aligned external peripheral grooves 102a will be spaced 120 degrees apart.

When the packer body 10 is pulled upwardly, in order to set the lower slips 22 against the casing, the first action is to shear the lower screws 23. Almost simultaneously, the metallic bridges 108 between the main segment portions 100a of the slip sleeve are disrupted by the wedging action of the expander 24, which breaks the sleeve into three main segments 100a, or places them in essentially the same condition as the upper slip segments 100. Thereafter, each lower slip segment 100a is guided outwardly, until it engages the well casing B, by the locating and guide pins 104a extending upwardly from the washer or disc 106. When sufficient wedging force is exerted on each slip segment 100a, it will break at its other weakened portions into a plurality of smaller segments.

It is unnecessary for the upper segments 100 to be initially formed as a solid integral sleeve, inasmuch as any foreign particles or substances that might engage the upper slips, during lowering of the equipment in the well casing, could not urge such slips outwardly toward the well casing. Instead, the tendency is for such slips to be urged and maintained in their retracted position. This is not true of the lower slips 22, however, since any upward force imposed upon them tends to shift them upwardly along the lower expander 24 and radially outward against the well casing B.

The upper slips 18 are held in retracted position by the shear screws 19 alone, which can be made to disrupt at a predetermined force within relatively close limits. The metallic bridges 108, however, may have a great variation in the force required to disrupt them, but this is of no material importance in connection with the lower slips 22, since the upward movement of the packer body 10 will, in any event, effect a disruption and expansion of the slips 22, and with a force which is much less than the force required to disrupt the release stud 57. The parts may be so related in strength as to insure that the upper slips 18 will first be anchored against the well casing B, the packing sleeve 29 expanded against the well casing, and the lower slips 22 then moved upwardly along the lower expander 24 and outwardly into engagement with the well casing.

The invention described herein relating to the slip arrangements and the guiding of the slips between retracted and expanded positions is both described and claimed in my divisional application for "Subsurface Well Tool," Serial No. 246,106, filed September 11, 1951.

The inventor claims:

1. In well apparatus: a well tool to be set in a well bore; a setting tool detachably secured to said well tool, said setting tool comprising latch means engageable with said well tool, means for holding said latch means in engagement with said well tool, means for exerting a force on said holding means which is transmitted from said holding means through said latch means to said well tool, said force exerting means

including a releasable connection connected to said holding means and intermeshing threaded elements, one of which threaded elements is secured to said releasable connection, and one-way lock means for preventing unscrewing of said threaded elements from each other, said lock means engaging at least one of said threaded elements to one side of the threaded engagement of said elements with each other.

2. In well apparatus: a well tool to be set in a well bore; means for setting said tool, including male and female elements threadedly engaged with each other; one-way lock means engaging said elements to prevent their relative rotation in one direction, said male element having a sufficient threaded length as to be capable of threading into said female element to an extent sufficient to shift said one-way lock means longitudinally along one of said elements and into a position where it is out of locking engagement with said one of said elements.

3. In well apparatus: a well tool to be set in a well bore; means for setting said tool, including intermeshing male and female elements threadedly engaged with each other; a helical lock spring engaging said elements to lock said elements against relative rotation in one direction, said male element having a sufficient threaded length as to be capable of threading into said female element to an extent sufficient to shift said lock spring longitudinally along one of said elements and into a position where it is out of locking engagement with said one of said elements.

4. In well apparatus: a body; normally retracted means on said body; a tool for exerting an upward force on said body and a downward force on said normally retracted means to expand said normally retracted means outwardly in a well bore; said tool comprising a latch member releasably coupled to said body, a retaining member engaging said latch member to hold it coupled to said body, upwardly movable means including intermeshing threaded members, a releasable connection between said upwardly movable means and retaining member, and one-way lock means engaging said threaded members to prevent their unthreading from each other, said lock means engaging at least one of said threaded members to one side of the threaded engagement of said members with each other.

5. In well apparatus: a body; normally retracted means on said body; a tool for exerting an upward force on said body and a downward force on said normally retracted means to expand said normally retracted means outwardly in a well bore; said tool comprising a latch member releasably coupled to said body, a retaining member engaging said latch member to hold it coupled to said body, an upwardly movable threaded member, a threaded tension rod threaded into said threaded member, a releasable connection between said rod and retaining member, and one-way lock means engaging said threaded member and rod to prevent their relative unthreading from each other, said lock means engaging said rod and threaded member to one side of the threaded engagement of said rod and threaded member with each other.

6. In a well apparatus: a body; normally retracted means on said body; a tool including means for exerting an upward force on said body and means for exerting a downward force on said normally retracted means to expand said normally retracted means outwardly in a well

bore; said upward force exerting means comprising a latch member releasably coupled to said body, a retaining member engaging said latch member to hold it coupled to said body, an upwardly movable threaded member, a threaded tension rod threaded into said threaded member, a releasable connection between said rod and retaining member, and a helical lock spring engaging said threaded member and rod outside of their threaded engagement with each other to prevent their relative rotation in one direction while permitting their relative rotation in the opposite direction.

7. In well apparatus: a body; normally retracted means on said body; a tool for expanding said normally retracted means outwardly, said tool comprising a latch member releasably coupled to said body, a retaining member engaging said latch member to hold it coupled to said body against relative longitudinal movement in one direction, movable means, a releasable connection between said movable means and retaining member whereby said movable means is operable to hold said retaining member against said latch member, and thrust means engaging said movable means and body to prevent said movable means and retaining member from moving in the longitudinal direction opposite to said one direction.

8. In well apparatus: a body; normally retracted means on said body; a tool for expanding said normally retracted means outwardly, said tool comprising a latch member releasably coupled to said body, a retaining member engaging said latch member to hold it coupled to said body against upward movement, movable means, a releasable connection between said movable means and retaining member whereby said movable means is operable to hold said retaining member against said latch member, and thrust means engaging said movable means and body to prevent downward movement of said movable means and retaining member relative to said latch member.

9. In well apparatus: a well tool to be set in a well bore; a setting tool detachably secured to well tool, said setting tool comprising latch means engageable with said well tool, means for holding said latch means in engagement with said well tool, means for exerting a force on said holding means which is transmitted from said holding means through said latch means to said well tool, said force exerting means including a releasable connection connected to said holding means and intermeshing male and female threaded elements, one of which is secured to said releasable connection, and one-way lock means in said female element and engaging said male and female elements to prevent unscrewing of said threaded elements from each other, said male element being capable of threading into said female element to an extent sufficient to shift said one-way lock means longitudinally along said female element to a position where it is out of locking engagement with said female element.

10. In well apparatus: a well tool to be set in a well bore; means for setting said tool, including male and female elements threadedly engaged with each other; and a helical spring in said female element connected to said male element and frictionally engaging said female element to one side of the threaded engagement of said elements with each other to prevent unscrewing of said elements from each other, said male element being capable of threading into said female element to an extent sufficient to shift

said spring longitudinally along said female element and out of frictional engagement with said female element.

11. In well apparatus: a body; normally retracted means on said body; a tool for expanding said normally retracted means outwardly, said tool comprising a member extending into said body, a releasable connection between said member and the lower portion of said body preventing upward movement of said member relative to said body, and means engaging said member and the upper portion of said body to prevent downward movement of said member relative to said body.

12. In well apparatus: a body; normally retracted means on said body; a tool for exerting an upward force on said body and a downward force on said normally retracted means to expand said normally retracted means in a well bore; said tool comprising a latch member adapted to be coupled to said body, a retaining member engaging said latch member to hold it coupled to said body, an upwardly movable threaded member, a threaded tension rod threaded into said threaded member, a releasable connection between said rod and retaining member, and a helical lock

spring in said threaded member connected to said rod and engageable with said threaded member to one side of the threaded engagement between said member and rod to prevent unscrewing of said rod from said threaded member while permitting further threading of said rod into said threaded member to an extent sufficient to shift said lock spring longitudinally along said threaded member and out of engagement with said threaded member.
